GAS TRAP

Warren C. Kimbrough, Omaha, Nebr.

Application February 27, 1937, Serial No. 128,208

3 Claims. (Cl. 48—193)

This invention relates to gas detectors, and more particularly to gas traps and has for an object to provide means for detecting whether or not a gas main or pipe in a street has become broken and to provide means for preventing poisonous fuel gases from entering a dwelling.

A further object of the invention is to provide means for the above stated purposes which are economical in construction and may be readily installed for use in connection with gas pipes theretofore buried in and below the service of the ground, said means adapted to warn the occupants of a dwelling of the escape of poisonous gas thereby giving opportunity to check dangerous gas leaks and for repairing the pipe conductors of said gas.

Other and further objects and advantages of the invention will be understood from the following detailed description thereof, reference being had to the accompanying drawing in which:

Figure 1 is a longitudinal vertical section of the invention installed in a position of use in connection with a pipe conductor of poisonous fuel gases, the view being taken substantially on line 25 1—1 of Figure 2.

Figure 2 is an end view of the said device.

Heretofore resultant from the intensive cold of winters, frost entering the ground and the like, as well as other causes, the alignment of gas pipes or mains becomes disrupted, causing fuel gas to leak therefrom and since said pipes are buried below the surface of the ground the gas does not escape to the atmosphere, but follows along the loose earth about and specially adjacent the bottom of the pipe, seeking an escape specially as the pressure supplied by the main increases, whereby the gas follows lateral branches of the main and enters basements of dwelling houses poisoning the occupants thereof and said causes during the preceding winter in the city of Omaha, Nebraska, did occasion several fatalities to the sleeping occupants of several dwelling houses and it is an object of the invention to obviate the undesired practices of the prior art.

Referring now to the drawing for a more particular description, 10 indicates a pipe conductor of and for gas, the latter normally flowing through the pipe in the direction of the arrow 11, the normal position of said pipe being below the surface 12 of the ground 13.

It will be understood that the end 14 of the pipe is in communication with a supply of gas under pressure from a main, not shown, buried under the surface of an adjacent street and that

the end 15 of said pipe is closely adjacent to and enters through a basement wall or a dwelling, not shown, for supplying gas for conventional fuel purposes in a well known manner. At this time the pipe 10 is installed in a trench and loose earth 5 filled into the trench about the pipe. In many instances said earth settles away from the bottom of the pipe, providing thereby an open passageway through which gas which escapes from a broken main may flow or is forced by pressure of 10 gas escaping from the said main in instances where the latter is broken, said gas following along said passageway and traversing the bottom of the pipe and entering a dwelling through the brick walls of the basement, particularly in instances where the foundations of the dwelling do not extend below the pipe 10, and the new device is adapted to prevent deadly and noxious gases from entering said dwelling.

The gas trap of the present invention includes 20 a hollow housing having side walls 16 and end walls 17 which are joined together providing a frame which is rectangular in plan, said housing having an open bottom, the lower edges 18 of said walls are disposed below the level of the 25 pipe 10, in use. Opposite disposed notches 19 being provided in oppositely disposed side walls for permitting the housing to be lowered, whereby the oppositely disposed side walls of said notches receive the pipe 10, therebetween and whereby 30 the pipe 14 extends longitudinally through said housing and notches, a hole having been first dug from the surface 12 of the ground to a point below and in vertical alignment with the pipe 10.

The housing is preferably manufactured with 35 a detachable roof 20, the latter being preferably of pyramidal shape, having an outlet 21 at the top portion or apex thereof and flanges 22 at the base of said pyramid, said flanges extending in parallelism with the walls 16 and 17, the latter 40 being provided with complementary receiving troughs 23 for the flanges as shown in Figure 1.

The outlet 21 is preferably provided with an upstanding neck 24 adapted to receive thereover a conduit 25 which during installation may be 45 riveted or otherwise suitably secured to said neck.

A conduit 25 extends above the surface 12 of the ground and is preferably provided with a gooseneck or semi-circular portion 26 whereby the free end of the conduit or the open end 27 thereof is closer to said surface 12 than the semi-circular portion 26 for preventing débris from entering the housing through the conduit such as might otherwise enter by means of unauthorized persons, children or the like placing said débris 55

in said conduit and, if desired, a screen may be placed across the open end of said conduit and secured to the latter.

As best shown in Figure 2, one of the notches 19 is of lesser transverse width than the other, said notch of lesser width being disposed towards the dwelling and means are provided for plugging or closing said notch, said means preferably comprised of split washers which collectively are 10 adapted to encircle the pipe 10 and abut the latter for said purpose, said washers being secured to the adjacent wall 16 during installation, whereby gas is prevented from flowing outwardly of the housing and toward said dwelling along said pipe 15 and through said notch.

The notch opposite to said smaller notch is of larger area or transverse width than the diameter of the pipe 14 and remains open in use for permitting gas following along the pipe 10 from 20 said main to enter the housing or trap through said wider notch.

The roof of the housing is preferably manufactured removable from the walls thereof to facilitate installation and shipping and after 25 said hole is dug in the ground the walls are lowered and installed as above described, the roof being detached at this time, whereby the operator may stand within the walls and settle the latter firmly into the ground, packing earth upwardly of the walls above the lower edges 18 thereof and securing the washers for plugging the smaller notch as above described.

At this time if so desired, the operator may install a transverse disposed rod or support 28 35 under the pipe 10, as shown in Figure 1, for preventing frost or the like from heaving said walls upwardly of their selected position with respect to the pipe 10. The roof is now placed on the walls and cement may be applied to the member 40 23 for sealing the flanges 22, if desired. The conduit 25 being placed in position, earth is replaced about the device and upon the roof thereof until said earth reaches the level 12 or surface of the ground.

45 In operation escaping gas following along the pipe 10 as above described enters the hollow housing, but is prevented from entering the dwelling, said gas escaping through the outlet 21 of the roof and the occupants of the dwelling upon detecting an escape of gas by sense of smell 50 may apprise workmen that the main should be repaired. In instances where several of the new devices are installed at different points along the street, the place where the main is broken may be more readily located thereby for repair thereof at a lessened cost for the same and as compared to uncovering an extensive length of main 55 for locating a leak.

Preferably the end walls 17 of the device are 60 each provided with an outstanding hood 29 having open bottoms and roofs 30 which are inclined upwardly and toward said side walls, said hoods functioning to collect gas which may be present about said housing but not entering the latter 65 through the latter notch 19, said hoods being of particular advantage when installed in loose or sandy soils.

Preferrably the roof 20 is provided with a plurality of hoods 31 having open ends which function for the same purpose as the hoods 29 in connecting stray gases and concentrating the same for discharge or escape through the outlet 5 21, whereby detection of gas leaks is facilitated.

It is obvious that various changes and modifications may be made in the details of construction and design of the above specifically described embodiment of this invention without departing 10 from the spirit thereof, such changes and modifications being restricted by the scope of the invention as claimed.

What is claimed is:—

1. A gas trap comprising a hollow housing 15 having side walls, means for permitting the application and withdrawal of the housing without disturbing the fuel gas pipe to which it is applied including a roof and an open bottom, oppositely disposed side walls being provided with notches 20 opening from the bottom edge of said walls, oppositely disposed side walls of said notches adapted to be lowered about and receive therebetween a pipe conductor of fuel gas while the latter is disposed below the surface of the ground, 25 whereby said pipe extends through said notches and said walls, and the lower portions of said walls are disposed below said pipe, one of said notches being of such a width with respect to the diameter of said pipe that escaped gas may enter 30 said housing therethrough, and means adapted to encircle and abut said pipe for closing the other of said notches for preventing passage of gas therethrough, said roof provided with an outlet adapted to be disposed above the surface of 35 said ground for permitting communication of gas from the housing to the atmosphere.

2. A gas trap comprising a hollow housing 40 having side walls, a roof and an open bottom, means on oppositely disposed side walls for permitting fuel gas pipe to pass through said housing with the lower portions of said side walls extending below said pipe and for permitting entrance of escaped gas to the housing through one side wall and preventing passage of said escaped gas through said side walls, means carried 45 by the roof for conducting the escaped gas to the atmosphere, and hood means on said housing for collecting other escaped gas within said housing comprising a plurality of hoods each having an open bottom communicating with the interior 50 of the housing and a closed top.

3. A gas trap comprising a hollow housing having side walls, a roof and an open bottom, means on oppositely disposed side walls for permitting fuel gas pipe to pass through said housing with the lower portions of said side walls extending below said pipe and for permitting entrance of escaped gas to the housing through one side wall and preventing passage of said escaped gas 60 through said side walls, means carried by the roof for conducting the escaped gas to the atmosphere, and means cooperating with said pipe for maintaining the housing in operative position.

WARREN C. KIMBROUGH.
